CLAIM

The ornamental design for a modular storage and display unit, as shown and described.

DESCRIPTION

FIG. 1 is a perspective view of a modular storage and display unit showing my new design;
FIG. 2 is a front elevational view thereof;
FIG. 3 is a left side elevational view, the right side being a mirror image thereof;
FIG. 4 is a rear elevational view thereof; and
FIG. 5 is a top plan view thereof.

FIG. 1.

FIG. 2.

FIG. 3.

FIG. 4.

FIG. 5.
